UNITED STATES PATENT OFFICE.

GEORGE G. RAY, OF BOSTON, MASSACHUSETTS.

STEAM REED INSTRUMENT.

Specification of Letters Patent No. 29,915, dated September 4, 1860.

To all whom it may concern:

Be it known that I, GEO. G. RAY, of Boston, in the county of Suffolk and State of Massachusetts, have invented an Improved 5 Instrument for Producing by the Action of Steam an Alarm or a Musical Sound, of which the following is a full, clear, and exact description, reference being had to the accompanying drawings, making part of this 10 specification, in which—

Figure 1, is a view of an alarm to be connected with a steam boiler, for sounding an alarm when required; Fig. 2, a vertical section through the middle of the same.

15 My present invention consists in a vessel or chamber communicating with a steam boiler, and having one or more orifices for the escape of the steam which is admitted to it, each orifice being covered by a reed so 20 that the escaping steam will produce a musical sound, which may be used for an alarm or a signal, or by a combination of a number of such chambers and reed covered openings a musical instrument may be produced.

25 That others skilled in the art may understand and use my invention I will proceed to describe the manner in which I have carried out the same.

In the said drawings A, is a circular band 30 of stout brass or other suitable metal, to which is attached a cap B, and a bottom C. The latter screws on to the edge of the band at *a*, and is furnished with an opening *b*, and a screw *c*, to which a pipe may be attached to 35 connect it with a steam boiler. This forms a steam chamber D, to which steam is admitted from the boiler when desired by an ordinary valve or stove cock (not shown in these drawings) which may be placed in any convenient part of the pipe which connects the

chamber D with the boiler. The band A, has cut through it a series of long narrow slots or openings *e*, over each of which is soldered on the inside of the band, a plate *f*, in which is cut a slot *i* somewhat smaller 45 than the one in the band opposite to it. Over this latter slot is placed a thin strip of metal *m*, known in musical instruments as a reed, which is riveted at 5 to the plate *f* before the plate is soldered on. The reed is of 50 a size at its lower part to just fit the slot *i*, but is enlarged at its top where it is riveted at 5. The plate *f* is thinned down toward the edges of the slot *i* as shown at 6 Fig. 1.

When steam is admitted to the chamber D, 55 its escape through the slots *i* produces a vibration of the reeds *m*, and gives a musical sound which may be varied by the size of the orifice and the reed.

The chamber A, may be of any convenient 60 form or a number of chambers, each furnished with a slot and reed, and commanded by a suitable stop or valve, may be combined together to form a musical instrument, to be operated by steam.

65 The above instrument when used as a signal or alarm, may be made to produce a much more agreeable sound than the harsh sounding steam whistle now in general use.

What I claim as my invention, and desire 70 to secure by Letters Patent, is—

The chamber D communicating with a steam boiler, and furnished with one or more orifices or slots *i* and corresponding reeds *m*, substantially as described for the purpose 75 specified.

GEO. G. RAY.
